UNITED STATES PATENT OFFICE.

WILLIAM F. BOWERS, OF SAN FRANCISCO, CALIFORNIA.

DESIGN FOR RUBBER HOSE.

40,763.

Specification for Design. Patented July 12, 1910.

Application filed March 11, 1910. Serial No. 548,753. Term of patent 14 years.

To all whom it may concern:

Be it known that I, WILLIAM F. BOWERS, a citizen of the United States, residing in the city and county of San Francisco, State of California, have invented a new, original, and ornamental Design for Rubber Hose, of which the following is a specification, reference being had to the accompanying drawing, forming part thereof, wherein is dis-

closed a perspective view of a rubber hose showing my new design.

I claim:

The ornamental design for rubber hose, as shown.

WILLIAM F. BOWERS.
